PORTABLE PISTON GROOVER AND FACER

Gustave W. Berggren, Brooklyn, N. Y., assignor
to Charles W. Berggren, Brooklyn, N. Y.

Application October 1, 1938, Serial No. 232,793

9 Claims. (Cl. 82—4)

The invention relates to portable apparatus for re-grooving pistons, for re-facing cylinders, and for other similar work. The apparatus can be carried to the place where the work is to be performed, thereby making it possible to perform the desired work without dismantling an engine or other apparatus to carry a part thereof to a shop.

My portable apparatus, in its preferred form, is particularly adapted to re-grooving the pistons of large engines such as Diesel marine engines or large stationary engines. It will be understood that such pistons are extremely heavy, often weighing a ton or more, and are difficult to handle; nevertheless the usual practice is to remove the pistons from the engines and carry them to a machine shop where the necessary work can be performed. This procedure involves considerable cost in trucking and in providing the necessary apparatus at the machine shop for handling and supporting the pistons. There is also, in such procedure, a substantial danger of injury to workmen in handling the pistons and performing the work in the shop. When my apparatus is used it is possible to carry the apparatus to the vessel or other place where the engine is located and to perform the desired work on the pistons thereof without dismantling the engine.

The primary objects of the preferred form of my invention are therefore to enable the desired work to be done satisfactorily with the minimum of cost and inconvenience and with the maximum of safety and to do away, in large part, with heavy machinery which is ordinarily required to follow out the usual procedure. I am aware that suggestions have been made as to the construction of portable apparatus for re-grooving heavy pistons but, so far as I know, no such apparatus has been entirely successful. In the use of my apparatus, the portable piston groover and facer can be carried to the work; the cylinder head of the engine removed; the piston withdrawn from the cylinder a sufficient distance to make the grooves thereof available for re-grooving by the use of my apparatus; my apparatus mounted on the piston itself and adjusted with respect to the grooves therein; and then operated practically automatically from a suitable source of power associated therewith. My apparatus, as will be understood by those skilled in the art, with proper modification of the cutting tools or otherwise, may also be used for facing cylinders and, as in the case of re-grooving, this work may be done at the place where the engine is located.

Other objects and advantages of my invention

will be apparent from the following specification taken in connection with the drawings, in which—

Figure 1 is a perspective view, with a portion of the apparatus cut away, of the preferred form 5 thereof;

Fig. 2 is a fragmentary elevation thereof, showing also a part of a piston, part of the apparatus being shown in a section taken on the line 2—2 of Fig. 1, looking in the direction of the arrows; 10

Fig. 3 is a sectional elevation of the ring or carriage and tool post, showing the radial adjusting means and a tool holder and tools, the section being taken on the line 3—3 of Fig. 4;

Fig. 4 is a vertical section of the tool post and radial adjusting means, the section being taken on the line 4—4 of Fig. 3 looking in the direction of the arrows;

Fig. 5 is a fragmentary plan view of the tool post and associated tool holders and a tool, part 20 thereof being shown in section on the line 5—5 of Fig. 3, looking in the direction of the arrows; and

Fig. 6 is a fragmentary plan view of the tool post, showing the means for axially adjusting 25 the tool holders.

I will now describe the preferred form of my invention by reference to the drawings in which the numeral 10 indicates a piston which it is desired to re-groove, the grooves for the piston rings being shown at 11. As above stated, the piston is made available for the re-grooving operation by removing the cylinder head of the engine and raising the piston and supporting it as, for example, by I-beams resting on the cylinder block. To support my apparatus on the piston, I provide right-angle brackets having a plate 12 which may be curved so as to have the same radius curvature as the outer surface of the piston. The plates 12 are provided with wings 13 having apertures therein. Preferably four such brackets are provided. They are equally spaced around the lower exposed portion of the piston and then tied tightly together, as by the bolts 14 which pass through the apertures in the wings and are held in position by the nuts 15 so as to hold the brackets rigidly in place. Each bracket is provided with an outwardly extending plate 16 to which the remainder of my apparatus is clamped.

The tool carriage, tool holders, etc., are supported on a cylindrical web 17, hereinafter referred to as the bed. The bed is provided with annular flanges 18 and 19; the flange 18 is located at the bottom thereof and provides means 55

for clamping the bed to the brackets, and the flange 19 is located at the top of the web and acts as a bearing for the tool carriage. The bed is rigidly attached to the projecting plates 16 of the brackets by means of clamping members 20 and bolts 21 which pass through apertures in the members 20 and the plates 16 and are held in place by nuts 22.

The carriage upon which the tool holders are mounted is rotatably associated with the bed. In its preferred form, the carriage is made up of a ring gear 23 provided with external teeth 24 to which are affixed a guard ring and members provided with beveled grooves in which the tool carriers are adjustably mounted. A suitable source of power, such as the electric motor 25, is provided, preferably mounted on the bed as by the brackets 26. The motor, through pulleys 27 and a belt 28, drives a worm gear train (not shown) enclosed in the housing 29. Connected to the spur-wheel or driven wheel of the worm gear train is a pinion 30 which meshes with the teeth 24 on the ring 23 and thereby rotates the ring at a suitable speed. I have found that a peripheral speed for the ring of about three feet per minute is suitable for re-grooving Diesel engine pistons.

The ring 23 is rotatably associated with the bed by means of clamping members 31, preferably four in number, each of which, in the preferred form shown, comprises a plate which carries two flanges 32 that extend downward over the inside edge of the annular flange 19 of the bed. Bolted to the lower edge of each flange 32 is a small plate or keeper 33 which extends under the inside lower surface of the flange 19. It will of course be understood that the clamps formed by the flanges 32 of the members 31 and by the keepers 33 are sufficiently loosely associated with the flange 19 to permit the ring 23 to rotate with respect to the bed. I also preferably provide other keepers 34 which are bolted to the under side of the ring 23 and which extend under the outside lower surface of the flange 19. The ring is thus rotatably mounted on the bed in such manner that rotary motion is the only possible motion thereof. Guard members 35, of channel iron, may be provided; these are also bolted to the ring 23 as shown in Fig. 2. The bolts 36 thus extend through and clamp together the keepers 34, the ring 23, the members 31, and the guard member 35, the bolts being held in position by associated nuts. For ease in assembling my device, I prefer to make the guard member in four parts.

The members 31, in addition to carrying the flanges 32, also carry upstanding and inwardly turned ribs 37 which, together with the intervening surface 38 of the member 31, provide beveled grooves in which the tool carriers are mounted in such manner that they are slideable radially therein. In general, in the preferred form of my apparatus, the tool carriers comprise a T-shaped tool post 39, the horizontal portion of which is dovetailed in the groove provided by the member 31 and the upstanding ribs 37 thereof. If desired, the width of the horizontal portion of the tool post may be made somewhat smaller than the width of the groove and gibs (not shown) inserted between the tool post and the ribs 37 of the member 31 to adjust the amount of friction between the tool post and the ribs 37.

Mounted on the surface 38 of each member 31, inside of the horizontal portion of the tool holder, I provide a threaded nut 40. The outer end of

the horizontal portion of the tool post is closed by a plate 41 suitably affixed thereto, as by the bolts 42. This plate is apertured and one end of a feed screw 43 passes through the aperture. The threaded portion of the feed screw 43 extends within the horizontal portion of the tool post and through the threaded aperture in the nut 40, engaging the threads therein. The threaded portion of the feed screw 43 is made larger than its outer end so as to provide a bearing surface on the inner side of the plate 41. On the outer side of the plate 41, a collar 44 is provided which is affixed to the feed screw by a set screw and which provides a bearing surface on the outer side of the plate 41. The outer end of the feed screw 43 is provided with a star-wheel 45, the purpose of which will be hereinafter explained. As will be seen from the foregoing, the radial position of the tool post with respect to the ring 23 and associated members may be adjusted by rotation of the feed screw 43.

The vertical portion of the tool post consists of a plate 46 having vertical ways 47 on which the tool holders 49, which will be hereinafter described, are slidably mounted. The ways 47 are so shaped as to provide channels 48, the function of which will be hereinafter explained. The tool holders 49 are so formed as to dovetail with the ways 47 so that the tool holders can slide up or down on the tool post but cannot move in any other direction. Each tool holder is provided with a vertical face 50 preferably making an acute angle with the radial plane of the ring 23 which passes through the tool post. Each tool holder also carries a projection 51 which extends into the corresponding channel 48 in the vertical portion of the tool post and is provided with a threaded aperture 52. To the top of the vertical portion of each tool post plates 53 are affixed, as by bolts or screws 54, each plate being provided with an aperture through which one end of a threaded rod 55 passes. These rods are similar to the feed screws 43 and perform a similar function. Like the feed screws 43, the portion of each rod 55 that is threaded is enlarged to form a surface which bears against the under side of the plate 53. Each rod 55 also carries a collar 56 which similarly provides a bearing surface on the upper side of the plate 53. The tops of the rods 55 are squared, as indicated at 57, in order that cranks 58 may be mounted thereon to turn the rods. The threaded portion of each rod passes through the aperture 52 in the projection 51 on the corresponding tool holder. In this manner, means are provided for adjusting the vertical or axial position of each tool holder.

The faces 50 of the tool holders are provided with threaded bolt holes 59 adapted to receive bolts 60. Cutting tools 61 are clamped in desired position between the faces 50 of the tool holders and plates 62 which are held in position by the bolts 60.

I preferably provide a projecting post or tongue 63, mounted on the bed 17. This tongue is so positioned that it will engage the points on each star-wheel 45 as that wheel passes the tongue on each revolution of the ring 23 and the associated parts of the apparatus. In this manner, means are provided for automatically moving the tool posts, and therefore the tools themselves, progressively in a radial direction. In the form of apparatus shown in the drawings, the progressive motion is inwardly so that the tools 61 at first engage merely the outer edges of the 75

grooves 11 in the piston and are then progressively moved inwardly until the re-grooving operation has been completed.

It will be understood that, in the form of my apparatus as shown in the drawings, only one tool post may be used, if desired, for any particular operation and also that two or three or four may be used; the maximum number that can be used may be increased by the addition of more 10 clamping members 31. Likewise, any desired number of tool holders and of tools may be used, the number of each to be used depending upon the particular character of work to be performed in each case and also upon convenience of assembly and adjustment. Preferably, however, the tool posts that are in place at any one time should be evenly spaced around the ring 23 to balance the apparatus and equalize thrusts. It is also desirable to consider the matter of balance 20 and of equalization of thrusts in determining the number of tool holders and tools to be used, although this is not ordinarily essential.

When it is desired to use my apparatus to re-groove pistons, particularly those that are too 25 bulky or heavy to be easily removed from the engine, my apparatus will be carried to the place where the engine is in order that the work may be done there. The cylinder head of the engine will first be removed and then the piston raised 30 and supported on the engine block or otherwise, as above described. The four brackets 12 are then spaced around the lower part of the piston and the bolts 14 inserted and the brackets tightly tied together by means of the bolts and associated 35 nuts 15. The bed 17 and remainder of the apparatus which is carried thereby, with as many tool posts and tool holders in place as desired, is then lowered over the piston so as to rest on the four outwardly extending plates 16 of the brackets. The bed is then clamped to these 40 plates by means of the members 20 which engage the lower flange 18 on the bed and are held in place by the bolts 21 and associated nuts 22. The tool posts 39 are then moved outwardly a 45 sufficient distance to permit as many tools 61 as desired to be clamped to the faces 50 of the tool holders. The axial position of the tools is then adjusted by means of a crank 58 which rotates the threaded rods 55. The radial position 50 of the tools is then adjusted by rotation of the feed screws 43. The tools having thus been adjusted to their desired positions with respect to the grooves in the piston, the motor 25 is started and the re-grooving operation thereby 55 commenced. After the re-grooving operation has been completed the tools are withdrawn from the grooves by backing out the tool posts by means of the feed screws 43. If all of the grooves in the piston have not been re-grooved 60 in this first single operation, the tool holders are re-adjusted so that the tools will operate upon such other grooves in the piston as still require re-grooving. It will thus be seen that I have provided a portable piston re-grooving machine 65 which may be brought to the work instead of bringing the work to the shop and which, after preliminary adjustment, completes the re-grooving operation automatically.

As above stated, my invention has other uses, such, for example, as the re-facing of cylinders. To accomplish this, as will be obvious to those skilled in the art, no change in the principle of operation of my apparatus will be required. The only modifications in the preferred form thereof, as shown and described herein, that will be

necessary will be to make the apparatus of suitable size to perform the desired work, to provide suitable means for holding my apparatus rigidly with respect to the article upon which the work is to be performed—such means being used in substitution for the brackets 12; to turn the tool posts around in the grooves which carry them so that the vertical portions thereof are on the outside of the ring and bed; and to substitute cutting tools of the desired form. If automatic radial motion of the tools is desired, the tongue 63 may be affixed to the inside of the bed and thus extend inwardly instead of outwardly. I have not shown these modifications herein because of their obviousness.

It will also be understood by those skilled in the art that many other modifications or changes may be made in the form and arrangement of parts without departing from the spirit of my invention.

I accordingly desire protection for all such modifications or changes in my apparatus as may come within the scope of the appended claims.

I claim:

1. In a device of the kind described, a cylindrical member provided with an annular flange; means for positioning said member rigidly with respect to the article upon which work is to be performed; a ring carrying clamping means slidably engaging said flange; a ring gear carried by 30 said ring; a source of power affixed to said member; means associated with said source of power and engaging said ring gear to rotate said ring; and tool-carrying means adjustably mounted on said ring.

2. A device according to claim 1 in which the tool-carrying means comprises a tool-post which is adjustable with respect to the ring, and a tool-holder carried by the tool-post and adjustable with respect thereto.

3. A device according to claim 1 in which the tool-carrying means comprises a tool-post which is radially adjustable with respect to the ring and a tool holder carried by said tool-post and adjustable in an axial direction.

4. A device according to claim 1 which is provided with automatic means for progressively moving said tool-carrying means in a radial direction.

5. A portable piston groover comprising in 50 combination a circular bed, means for rigidly mounting the bed with respect to the piston and in spaced relation thereto, a circular member rotatably carried by said bed, means associated with the bed for rotating said member, a tool post 55 mounted on said member, and a tool holder mounted on said tool post, said holder being both axially and radially adjustable with respect to said member.

6. In a device of the kind described, the combination comprising a bed, means for affixing the bed to the article upon which work is to be performed, a ring carried by the bed, the ring being provided with an annular gear, a radial way rigidly carried by the ring, a tool post having 60 radial and axial arms, the radial arm of which is mounted in said way and radially movable with respect to said ring, a way carried by the axial arm of the tool post, a tool holder mounted in said last mentioned way and axially movable 65 with respect to said ring, and means for rotating said ring with respect to the article upon which work is to be performed.

7. In a device of the kind described, the combination comprising a bed adapted to surround 70

- the article upon which work is to be performed, means for rigidly mounting the bed with respect to the article, a circular member rotatably carried by said bed, a source of power carried by said bed, an annular gear carried by said circular member, means associating said gear with said source of power whereby said circular member may be rotated, a tool post having radial and axial arms, the radial arms being adjustably mounted on said circular member, and a tool holder carried by the axial arm of said tool post and adjustable with respect thereto.
8. In a device of the kind described, the combination comprising a cylindrical member, means for mounting said member rigidly with respect to the article upon which work is to be performed, said member being spaced from said article, a ring rotatably mounted on said member, means for rotating said ring, a tool post provided with radial and axial portions, the radial portion being mounted on said ring and radially adjustable with respect thereto and the axial portion thereof extending into the space between
